SAWMILL HEAD BLOCK ADJUSTING DEVICE

William T. Frazier, Kinston, N. C.

Application March 28, 1945, Serial No. 585,221

4 Claims. (Cl. 143—114)

1

My present invention, in its broad aspect, has reference to improvements in means for adjusting saw mill head blocks so that a log having a greater diameter at one end than the other may be properly supported on the frame. According to present practice, a log is mounted on a saw mill carriage which consists of a frame supported on trucks. The frame carries sliding head blocks having knees engaging the surface of the log. Since logs are almost always of greater diameter at one end than the other, the blocks must be moved with respect to the frame to adjust them and the knees against the log to properly support the log.

My present invention has reference in its more specific aspects to a simple and effective device for relatively adjusting the head blocks with respect to the log by a single attendant whether the log be tapered or straight, and to that end, I provide a shaft on which three spaced gears are keyed, such gears being the drive gears for the center head block and two end head blocks in a three block carriage. The center gear has ordinary transverse teeth and the teeth of the end gears are angled in a reverse direction so that the end head blocks are moved with relation to each other and the center head block to conform to straight logs and logs of tapered conformation. An ordinary manual gear and dog feed and operating handle is provided, and a single lever with a yoke is pivoted to move the shaft longitudinally to actuate the two end gears and blocks to adjust the same to variations in diameter and shape of the particular log acted upon.

Other and equally important objects and advantages of my invention will be apparent from the following description and drawings, but it is to be understood that changes in form, size, shape, construction and arrangement of parts is permissible provided same fall within the purview of my broad inventive concept and the scope of the appended claims.

In the drawings wherein I have illustrated a preferred form of my invention:

Figure 1 is a sectional view on line 1—1 of Figure 2 of a saw mill carriage assembly in which my invention is incorporated.

Figure 2 is a top plan view.

Figure 3 is a transverse section on the line 3—3 of Figure 1.

Figure 4 is a section on the line 4—4 of Figure 1, and

Figure 5 is a transverse section on the line 5—5 of Figure 1.

In the drawings wherein like characters of ref-

2

erence are used to designate like or similar parts throughout the several views:

The numeral 1 designates a saw mill carriage having a frame 2 and trucks 3 mounted on tracks

4. The frame has side stringers 5 and cross pieces 6. See Fig. 5. Mounted transversely of the frame are three head block assemblies 7, 8 and 9. The log (not shown) is disposed longitudinally of the frame on the three head blocks 10 and since logs differ in diameter and in amount and type of taper, it is desirable to adjust the end blocks with reference to the center head block and with reference to each other to compensate for the taper of the log.

15 To that end, I provide a base piece 10 for each head block which is attached to the frame as at

11. Each base is rectilinear in cross section and hollow and has a bottom wall 12, side walls 13 and a slotted top wall 14. Knees 15 have slotted

20 bases 16 into which the sections of the top wall slidably engage so that the knees may be moved across the bases. The base of each knee is formed with teeth 17. The teeth of the center knee 15 of center head block 8 has ordinary

25 transverse teeth; the knees 15 of the end head blocks have angled teeth and the teeth of the knee of head block 7 are angled in the opposite direction from the teeth of the knee on block 9. Extending longitudinally of the frame and

30 through the head blocks adjacent one end is a shaft 18 which is both rotatably and slidably mounted. On one of the side stringers of the frame adjacent the shaft 18 is a bifurcated bracket 19 having spaced arms 20 through which

35 the shaft extends. A pinion 21 is keyed to the shaft as at 22, and the shaft is slidable with respect to the pinion. Pivoted to the shaft between the arms 20 is the bifurcated end 23 of a hand lever 24. Between the arms of the bifurcated end 23 is a cross piece 25 in which is slidably mounted a dog 26 on the end of rod 27

40 carrying a collar 28 and a spring 29 for normally holding the dog out of engagement with the pinion 21. A cap 30 is mounted on the end of the rod which is slidable in the hand lever 24. By

45 these means, the shaft may be manually rotated simply by engaging the dog with the pinion and operating the hand lever.

50 Keyed to the shaft in such a manner that the shaft is fixed thereto are gears 31, 32 and 33. Gear 32 meshes with the teeth on the base of the knee of the center head block 8, and the teeth of gears 31 and 33 have opposite angularity to mesh with the teeth of the knees on the two end head

3

blocks 7 and 9. Gears 31, 32 and 33 are within the base pieces 10.

Attached as at 34 to the center head block base 10 is an arcuate rack 35. Pivoted as at 36 to the side stringer below the rack 35 is a hand lever 37 having an oval-like yoke 38 between its ends to the side bars 39 to which is pinned as at 40 a collar 41 engaging the shaft. A dog 42 on an operating rod 43 is carried by the hand lever 37 to engage in the teeth of the rack 35 and movement of the hand lever from right to left or vice versa slides the shaft and gears 31, 32 and 33 to dispose the same to independently adjust the knees of the end head blocks 7 and 9 with reference to each other and to the center head block, thereby to accommodate logs having different tapers, see dot-and-dash line A of Figure 2.

From the foregoing, it is believed that the operation and advantages of my invention will be apparent, but it is again emphasized that interpretation of the scope of my invention should only be conclusive when made in the light of the subjoined claims.

I claim:

1. An adjusting device for head blocks and knees in a saw mill carriage device having a frame having side and cross stringers, each cross stringer comprising a base member having a slotted top wall forming a track to slidably receive end and center knees, the end knees having bases formed with oppositely angled teeth, the center knee having a base with transverse teeth, three gears cut with teeth to mesh respectively with the teeth of the corresponding knees, a shaft to which said gears are fixedly connected, means for rotating the shaft, and means for sliding the shaft.

10
5

2. The invention as defined in claim 1 wherein the pivoted lever is fulcrumed to the frame stringer at its lower end and has an elongated oval-like yoke member formed above the fulcrum to the side rails of which is pivoted the collar on the shaft.

3. The invention as defined in claim 1 wherein both levers have dogs carried by operating rods, and the dog of one lever engages an arcuate rack to hold the lever in a pre-determined position, and the dog of the other lever engages a pinion keyed to the shaft to turn the shaft.

4. An adjusting device for head blocks and knees in a saw-mill carriage device having a frame having side and cross stringers, each cross stringer comprising a base member having a slotted top wall forming a track to slidably receive a knee, the center knee having a base with transverse teeth, the end knees having bases formed with oppositely angled teeth to be moved with respect to each other and the center knee to accommodate tapering logs, three gears cut with teeth to mesh respectively with the teeth of the corresponding knees, a shaft to which said gears are fixedly connected, means for rotating the shaft, and means for sliding the shaft.

WILLIAM T. FRAZIER.
